CLAIM

The ornamental design for a tub and shower faucet body, as shown and described.

DESCRIPTION

FIG. 1 is a front perspective view of the tub and shower faucet body showing my new design;

FIG. 2 is a rear perspective view thereof;

FIG. 3 is a top plan view thereof;

FIG. 4 is a front elevational view thereof;

FIG. 5 is a bottom plan view thereof;

FIG. 6 is a rear elevational view thereof; and,

FIG. 7 is a left side elevational view thereof, the right side being a mirror image of the left side.

The broken line showing of the handle, hose and hose connector in FIG. 2, of the hose connector in FIG. 1, and of the inner wall in FIG. 5 are for purposes of illustration only and form no part of the claimed design.
